UNITED STATES PATENT OFFICE

161,979

ANTENNA ROTATOR

Felix Weiss, Brookline, Mass.

Application July 20, 1950, Serial No. 11,269

Term of patent 14 years

(Cl. D26—14)

To all whom it may concern:

Be it known that I, Felix Weiss, a citizen of the United States, residing at Brookline, county of Norfolk, and Commonwealth of Massachusetts, have invented a new, original, and ornamental Design for an Antenna Rotator, of which the following is a specification, reference being had to the accompanying drawings, forming a part hereof.

Fig. 1 is a front elevational view of an antenna rotator, showing my new design;

Fig. 2 is a side elevational view;

Fig. 3 is a rear elevational view;

Fig. 4 is a top plan view; and

Fig. 5 is a bottom plan view thereof.

I claim:

The ornamental design for an antenna rotator, as shown.

FELIX WEISS.
